United States Patent Office

Des. 230,658
Patented Mar. 5, 1974

230,658

MATERIAL HANDLING BOX

William R. Powell, Hubbard, Ohio, assignor to The Powell Pressed Steel Company

Filed Apr. 11, 1972, Ser. No. 243,108

Term of patent 14 years

Int. Cl. D9—03

U.S. Cl. D87—1 R

FIG. 1

FIG. 2

FIG. 3

FIG. 4

FIG. 1 is a perspective view of a material handling box showing my new design;

FIG. 2 is a perspective view showing the side and end not seen in FIG. 1;

FIG. 3 is a perspective view showing a modified form of my new design; and

FIG. 4 is a perspective view showing the side and end not seen in FIG. 3.

The bottom is substantially plain.

I claim:

The ornamental design for a material handling box, as shown and described.
